UNITED STATES PATENT OFFICE.

FRED M. SHOTWELL, OF DETROIT, MICHIGAN, ASSIGNOR TO HERMAN W. KRUEGER, TRUSTEE, OF GREEN BAY, WISCONSIN.

CARD FILE.

Application filed August 6, 1927. Serial No. 211,127.

This invention pertains to improvements in card or document files and has primarily for its object to provide a simple, inexpensive, and durable file of either the drawer or 5 separate receptacle type, which automatically adjusts itself to accommodate varying numbers of cards, letters, folders, or documents, and retain them in a vertical position.

10 Incidental to the foregoing, a more specific object is to provide a card file with gravity means adapted to automatically adjust itself to the number of cards or documents contained within the file, container 15 or drawer, and hold them in a vertical position.

Another object is to provide a card file, container, or drawer, with a follower that will automatically adjust itself to any number 20 of cards and which is held against retrograde movement when the file is in its normal position.

A still further object is to provide a card file, of the foregoing characteristics, with 25 an improved cover, which when in use will neatly seat itself, and when not in use may be compactly nested with relation to the file, thus permitting the latter to be employed in a very compact space.

30 With the above and other objects in view, which will appear as the description proceeds, the invention resides in the novel construction, combination and arrangement of parts substantially as hereinafter de-

35 scribed and more particularly defined by the appended claims, it being understood that such changes in the precise embodiment of the herein disclosed invention may be made as come within the scope of the claims.

40 In the accompanying drawings is illustrated one complete example of the physical embodiment of the present invention constructed according to the best mode so far devised for the practical application of 45 the principles thereof.

In the drawings:—

Figure 1 is a transverse section through a file constructed in accordance with the present invention, the same being taken on the line 1—1 of Figure 2;

Figure 2 is a plan elevation;

Figure 3 is a fragmentary detailed section;

Figure 4 is a transverse section of a modified structure, the same being taken on the 55 line 4—4 of Figure 5;

Figure 5 is a longitudinal section taken on the line 5—5 of Figure 4;

Figure 6 is a transverse section illustrating a further modification;

Figure 7 is a side elevation of a still further modification;

Figure 8 illustrates a modified structure of follower.

Referring now more particularly to the accompanying drawings, that form of the invention illustrated in Figures 1 to 3 inclusive, comprises a file consisting of an open receptacle 1, preferably formed of metal and provided with side walls 2, which have formed therein a pair of inclined slots 3 for the reception of the ends of a follower 4.

It is to be noted particularly from Figures 2 and 3 that the follower is provided with reduced portions which form necks which fit within the slots 3. Outside of these necks, that is, at the outer ends of the followers, heads 6 are formed. These heads are enlargements of materially greater diameter than the necks.

As best shown in Figure 1, the slots are inclined downwardly toward the front of the file and their lower ends each terminate in an enlarged opening 5 which is of sufficient 85 diameter to receive the heads 6 formed on the ends of the follower 4.

From the foregoing explanation taken in connection with the drawings, it is obvious that gravity will cause the follower 4 to 90 automatically adjust itself to any number of cards, folders, or documents C, positioned within the file, and serve to hold the same in a vertical position, which renders them more accessible to the operator.

It will also be appreciated that the present structure is very simple and inexpensive to manufacture, in that practically no machine work is required in its assembly, the enlarged openings 5 at the ends of the slots 3 100 permitting the follower to be readily assembled in its operative position, and also permitting its removal should it be desired at any time to utilize the file without the follower.

Referring to the modification illustrated

60

70

105

in Figures 4 and 5, this structure differs primarily from that previously described in that the inclined slots 3' formed in the sides 2, are provided on their bottom edges 5 with a series of projections 11 adapted to prevent retrograde movement of the follower 4, after the same has been adjusted to the number of cards within the file and the file is placed in its normal operative position. Above the slots 3', are formed reinforcing ribs 6', which strengthen the material at this point, thus preventing bending and disalignment of the slots, with resulting binding or sticking of the follower.

15 It will also be noted that a novel form of cover 7 is provided which is pivotally and slidably secured to the file by means of pintles 8 which project through vertical slots 9 formed in the side walls 2 adjacent the 20 rear of the file. A clip 10 formed of a strip of sheet metal serves to hold the cover 7 in the desired nested position when the same is open.

In the operation of the modified structure 25 shown in Figures 4 and 5, the follower may be adjusted to the number of cards contained within the file either manually or automatically. In order to accomplish the foregoing automatically, it is merely necessary to tilt 30 the file forwardly to a vertical position which allows the follower to drop down to engage the stack of cards C, after which the file is then turned back to its normal position illustrated, which causes the follower 4 to be 35 held against retrograde movement by the projections 11 formed in the lower edges of the slots 3'.

From the foregoing, it will be appreciated 40 that a very simple and inexpensive structure has been provided which automatically adjusts itself to hold any desired number of cards contained within the file in an upright position, the retrograde movement of the follower being prevented by either the angle 45 of inclination of the slots or by the projections 11 illustrated in the modification. This latter structure is highly desirable where a file of great length is required, due to the fact that in such instances the angle of the 50 slots 3' must be necessarily reduced.

While two specific forms of the invention have been described in detail, namely that form utilizing the plain inclined slots, and the form provided with slots having projections to retard retrograde action of the follower, it is considered highly desirable in some instances to combine these features.

It is therefore proposed to accomplish this 60 by the structures disclosed in Figures 6 and 7. In that form shown in Figure 6 the sides of the receptacle are provided with corresponding slots 12, each having two portions, namely a plain inclined lower slot 13, and an upper slot 14 provided with projections 11, both slots serving their respec-

tive functions as heretofore explained in connection with the structures shown in Figures 1 and 4.

Figure 7 illustrates another arrangement of slots wherein each of the slots 12' are 70 provided with two inclined portions. In this instance the upper slot 13' is plain, while the lower slot 14' is provided with the projections 11.

It will be further noted from the modified structures, Figures 6 and 7, the manner of attaching the cover 7 to the receptacle is reverse from that shown in Figures 4 and 5, in that in this instance the sides of the cover are provided with slots 9', which receive the pins 8' carried by the receptacle, to permit both slideable and pivotal movement of the cover with relation to the receptacle. It will also be noted that the upper portions of the slots 9' are provided with an offset portion 9'', which, when the cover is nested on the receptacle in its open position, permits the same to swing back to a position slightly over the center and thus prevents accidental closing of the cover. A particular advantage of the foregoing manner of attaching the cover to the receptacle resides in the fact that it eliminates the necessity for a retaining clip such as that disclosed in Figure 4. 95

It will be further seen that a very simple form of cover has been provided which when not in use may be compactly nested to permit use of the file in a limited space.

In Figure 8 is illustrated a modified structure of follower wherein means are provided for positively locking the follower in the slots of the container to prevent its retrograde action. In order to accomplish this, one end of the follower 4' is provided with a reduced portion 16 which projects through one of the slots 3 formed in the side 2 of the container. Projecting from the reduced portion 16 is a threaded shank 16' for the reception of a nut 17, the end of the threaded shank being preferably upset to prevent complete removal of the nut. In operation, the foregoing structure of follower permits the same to be adjusted up to the cards within the container and thereafter locked 105 by turning up on the nut 17 and binding the side 2 of the container between the nut and the shouldered portion of the follower. It will be appreciated that after the follower has been positively locked in its desired adjusted position, the file may be transported without danger of losing the cards, as in the case where retrograde action of a follower is prevented by gravity. 115

Although the invention has been described in considerable detail, such description is intended as illustrative rather than limiting, as the invention may be variously embodied within the scope of the appended claims. For example, the invention is readily ap- 120 125 130

plicable to a drawer or container of any description, instead of being confined to what is strictly termed a card file of the separate receptacle type. Likewise, in utilizing the 5 term "card file" it is intended that the same shall include a receptacle for the proper filing of any kind of papers, documents, letters, or the like.

I claim:—

- 10 1. In combination with a card, letter or document file, means automatically adjustable to engage any number of cards or documents within the file for holding the same in a vertical position, and means obstructing the retrograde movement of said first-mentioned means.
- 15 2. A card, letter, or document file provided with inclined tracks in its sides, and a follower slidably guided in said tracks.
- 20 3. A card, letter, or document file provided with inclined tracks in its sides, a follower slidably guided in said tracks, and means for obstructing the retrograde movement of said follower.
- 25 4. A card, letter or document file provided with corresponding inclined slots in its sides, and a follower slidably guided in said slots for engaging cards within the file.
- 30 5. A card, letter or document file provided with corresponding inclined slots in its sides, said slots having enlarged openings in one of their ends, a follower slidably guided in said slots, and heads formed on the ends of said follower for insertion through said enlarged openings.

6. A card, letter, or document file provided with corresponding inclined slots in its sides, a follower slidably guided in said slots, and projections in the lower edges of said slots to prevent retrograde movement 40 of the follower when the file is in normal position.

7. A card, letter, or document file provided with corresponding slots in its sides, 45 said slots being inclined downwardly towards the front of said file, a follower having its ends guided in said slots, means formed in the lower edges of said slots for retarding retrograde movement of said follower when the file is in its normal operative position, and a cover pivotally and slidably connected to said file adjacent its rear wall.

8. A card, letter, or document file comprising a box-like member having parallel 55 sides, each of said sides having a U-shaped slot with the arms of the U projecting towards the front of the box, the bottom edge of one of said slots being provided with notches, one of said slots slanting downwardly and forwardly towards said front edge, and a follower extending transversely of the card file and having ends slidably guided in said slots.

In testimony that I claim the foregoing 65 I have hereunto set my hand at Green Bay, in the county of Brown and State of Wisconsin.

FRED M. SHOTWELL.
